UNITED STATES PATENT OFFICE

JOSEPH L. SHULAR, OF BIG STONE GAP, VIRGINIA

MINE CAR

Application filed April 1, 1931. Serial No. 527,009.

This invention relates to mine cars and more particularly to a novel body construction adapted to have maximum rigidity and strength coupled with lightness.

5 Another object is to provide a novel body construction in which the shocks and strains are distributed throughout the body.

A still further object is to provide a car body having maximum load capacity for its 10 weight.

In the drawings:

Figure 1 is a plan view of a car constructed in accordance with this invention.

Figure 2 is a side elevation of the car.

15 Figures 3 and 4 are end elevations of the opposite ends of the car.

Figure 5 is a sectional elevation taken on the line V—V of Figure 1.

Referring more particularly to the drawings, the letter A designates a reenforced central portion of the car bottom which is composed of a plurality of transversely spaced inverted T-shaped beams 2 which extend the entire length of the car bottom. Heavy 20 wooden planks 3 are mounted on the flanges 4 of the beams 2 and extend the entire length of the car bottom.

Short lengths of planking 5 are secured to the under side of the planks 3 at each end to 30 form bumper sills, which sills have their ends reenforced by a bumper-plate 6.

Suitable coupling devices 7 are secured to each end of the bottom portion A and are connected by a draw-bar 8 which extends 35 along the entire car bottom.

Suitable bail members 9 are mounted transversely under the bottom portion A and are bent up along the side edges of said bottom portion A, then outwardly substantially 40 parallel with the top face of the bottom portion for an appreciable distance to form bottom extension supporting portions 10, and are then bent upwardly to form side wall supports 12.

45 Plates 13 and 14 are secured to the bail members to form the side walls and bottom extension portions, respectively, of the body, and the plates 14 overlap the planks 3 of the bottom portion A.

50 The plates 14 are cut away at longitudinally

spaced points to form clearance openings for the car wheels, which openings are closed by crowned cap members 15.

The endmost bails 9 extend under the short lengths of planking 5 forming the bumper 55 sills of the car and serve to bind these planks in position.

Bail brackets 16 are provided along each side of the car and are secured to the bail at a point adjacent the outer end of the bottom 60 extension supporting portion 10 and at a point under said central bottom portion A to reinforce and stiffen the structure.

Suitable metal strap members 17 extend 65 transversely across the top face of said bottom portion A parallel with the bail and overlie at least a part of the bottom extension plates, and bolts 18 pass through said straps, said planks, and said bail to secure 70 said parts together. Other bolts 19 pass through the straps, bottom extension plates and bails, and still other bolts 20 pass through the straps, draw-bar, center plank and bails to further secure all of the body parts together. 75

By thus securing the bottom parts, bails and draw-bar together all strains and shocks are distributed throughout the car structure instead of being localized in any one or group of parts so as to permit the use of a lighter 80 structure than would otherwise be possible, and the life of the car is materially increased.

The one end of the car body is closed by a rigid metal end member B while the opposite end is provided with a hinged gate member C.

The running gear of the car consists of four wheels 25 journaled on axles 26 mounted between transversely extending angle-iron members 27 on the bottom face of the bottom 90 portion A.

One pair of the wheels 25 is provided with brakes 28 operable from one end of the car by a lever 29 and associated linkage and rock-shaft mechanism. The brake mechanism will not be described further in detail 95 since it forms no part of this invention.

The main advantages of the novel structure described above result from the employment of the inverted T-shaped beams 2, 100

the bails 9, and bail brackets 16, and consist of providing a light, rugged construction in which all strains and stresses are distributed throughout the whole body.

5 While I have shown and described one preferred form of my invention, it will be understood that I do not wish to be limited thereto, since various modifications may be made without departing from the scope of 10 my invention, as defined in the appended claims.

I claim:

1. A mine car body construction comprising a heavy reinforced central bottom portion composed of a plurality of transversely spaced inverted T-shaped beams extending the entire length of the car bottom, heavy planks extending the entire length of said car and supported on the flanges of said T-shaped beams, a plurality of bails extending under said central bottom portion and bent upwardly along the side face of said bottom portion then bent outwardly for an appreciable distance on a line with the top face 25 of said bottom portion to form bottom extension supports and then bent upwardly to form body side supports, metal sheets secured to said bails to form sides and bottom extension portions of said body, and bail brackets secured to said bails at a point adjacent the outer end of the bottom extension supporting portions and at a point under said central bottom portion to reinforce and stiffen the structure.

2. A mine car body construction comprising a heavy reinforced central bottom portion composed of a plurality of transversely spaced inverted T-shaped beams extending the entire length of the car bottom, heavy planks extending the entire length of said car and supported on the flanges of said T-shaped beams, other short lengths of planking secured to the under side of said central bottom portion at each end to form bumper sills, a plurality of bails extending under said central bottom portion and bent upwardly along the side faces of said bottom portion then bent outwardly for an appreciable distance on a line with the top face of said bottom portion to form bottom extension supports and then bent upwardly to form body side supports, metal sheets secured to said bails to form sides and bottom extension portions of said body, and bail brackets secured to said bails at a point adjacent the outer end of the bottom extension supporting portions and at a point under said central bottom portion to reinforce and stiffen the structure.

3. A mine car body construction comprising a heavy reinforced central bottom portion composed of a plurality of transversely spaced inverted T-shaped beams extending the entire length of the car bottom, heavy planks extending the entire length of said

car and supported on the flanges of said T-shaped beams, a plurality of bails extending under said central bottom portion and bent upwardly along the side faces of said bottom portion then bent outwardly for an appreciable distance on a line with the top face of said bottom portion to form bottom extension supports and then bent upwardly to form body side supports, metal sheets secured to said bails to form sides and bottom extension portions of said body, bail brackets secured to said bails at a point adjacent the outer end of the bottom extension supporting portions and at a point under said central bottom portion to reinforce and stiffen the structure, an all-metal end rigidly secured in one end of said body and an all-metal end hingedly secured to the other end of said body.

4. In a mine car body construction a reinforced central bottom portion comprising a plurality of transversely spaced inverted T-shaped beams extending the entire length of the car bottom, and heavy wooden planks extending the entire length of said car and supported on the flanges of said beams.

5. In a mine car body construction a reinforced central bottom portion comprising a plurality of transversely spaced inverted T-shaped beams extending the entire length of the car bottom, heavy planks extending the entire length of said car and supported on the flanges of said beams, and means for securing said beams and said planks together as a unit, said means including outer bail members extending transversely of said bottom portion, inner strap members extending parallel to said bail members, and bolts extending through said beams, said planks, and said bails and straps.

In testimony whereof, I have hereunto set my hand.

JOSEPH L. SHULAR.
